AUTOMATIC PULSATORT FOR MILKING MACHINES

Cyrus Howard Hapgood, Nutley, N. J., assignor to
The De Laval Separator Company, New York,
N. Y., a corporation of New Jersey

Application October 17, 1940, Serial No. 361,539

24 Claims.

(Cl. 31—61)

The object of my invention is to provide an automatic pneumatic pulsator, more particularly intended and adapted to that type of milking machines in which alternate high and low pneumatic pulsations (usually atmospheric and partial vacuum) are transmitted to the outer chambers of double chamber teat cups and in which when the pulsator is shifted in one direction two pairs of teat cups are connected with high pressure and the other two pairs with low pressure and in which, when the pulsator is shifted in the other direction, the pressure connections to the two pairs of teat cups are reversed.

The invention also relates to that type of pneumatic pulsator which comprises a valve that not only establishes the alternate connections above specified but that acts as its own motor to effect the reversals of movement required to establish such connections, the most practicable form of which is that of a piston valve which is subjected to high pressure on one end and a low pressure on the other end to move it in one direction, and which in its movement in that direction makes the pneumatic connections required to reverse the pressures on its opposite ends to thereby move it in the opposite direction.

While the valve thus acts as its own motor in reversing the connections to the two pairs of teat cups, it would, if uncontrolled, have a high speed vibratory movement. To prevent such uncontrolled movement and to hold the valve at each end position for a predetermined period of time, I provide a diaphragm that separates the casing in which it is enclosed into two chambers and that is mechanically connected with the motor valve. Before the valve fully completes its movement in either direction, and at the same time that it reverses the pneumatic pressures on its two ends and at the same time that it reverses the pneumatic connections to the two pairs of teat cups, it acts to make the pneumatic connections required to immediately establish great pressure differences in the two chambers, thereby holding the valve from immediate reversing, following which air flows from the high pressure chamber to the low pressure chamber until the pressure difference is reduced to a predetermined minimum, that is, until the pressures are so nearly balanced as to allow the differential pressures on the valve to become effective to reverse it.

From the foregoing description it will be understood that the way in which the diaphragm controls the shift of the valve is the same in

both directions of movement of the valve. However, prior to (and during the major part of) the shift of the valve in one direction the nearly balanced pressures on opposite sides of the diaphragm are high and the sudden creation of greatly unbalanced pressure is effected by connecting one of the diaphragm chambers with low pressure; while prior to (and during the major part of) the shift of the valve in the opposite direction the nearly balanced pressures on opposite sides of the diaphragm are low and the sudden creation of a greatly unbalanced pressure is effected by connecting the same diaphragm chamber with high pressure.

In practical operation the source of high pressure is the atmosphere, while the source of low pressure is means to establish a partial vacuum equal to half an atmosphere. In the specific embodiment of the invention herein described, one diaphragm chamber is alternately connected with the atmosphere and with what may be conveniently termed "vacuum," while in the other chamber the high pressure, when established therein, nearly equals atmospheric pressure due to the flow of air from the first chamber to the second when the first is connected with the atmosphere, while the low pressure, when established, in the second chamber, falls nearly to half atmospheric pressure due to the flow of air from the second chamber to the first when the latter is connected with vacuum. The greater the difference between the area of the diaphragm and the areas of the piston ends, the more nearly the pressures in the two chambers approach an exact balance in order to allow the differential pressures on the motor valve to start its movement in either direction. By making the diaphragm of much larger area than the pressure areas of the motor valve, a large volume of air flow is required to release or "unbrake" the motor valve. This is advantageous in that it requires no very close throttling of the valve and at the same time permits a very rapid flow of air, thereby avoiding the necessity of a very critical regulation of the pulsator, and also insuring against clogging of the passage at the throttle with dirt or dust, which would render the pulsator inoperative.

A preferred embodiment of the invention is shown in the drawings, in which—

Fig. 1 is a longitudinal sectional view of the pulsator.

Fig. 2 is a section on the line 2—2 of Fig. 1.

Fig. 3 is a section on the line 3—3 of Fig. 1.

Fig. 4 is a section on the line 4—4 of Fig. 2.

Fig. 5 is a view, similar to Fig. 1, of the pulsator shifted to the right.

Fig. 6 is a view, similar to Fig. 1, of the pulsator shifted to the left.

Fig. 7 is a detail view of a simplified connection between the valve and the diaphragm.

The cylindrical body *a* of the pulsator is closed at one end by a cap *b* and opens at the other end into a casing *c*, which is divided, by a diaphragm *d*, into two chambers, preferably of cylindrical shape as shown, one of which, *t*, I designate as the lower, inner or main diaphragm chamber and the other of which, *u*, I designate as the upper, outer or secondary diaphragm chamber.

The inner wall of the pulsator body *a* is lined with a bushing *e* the end of which abuts against a washer *f* confined between the closure cap *b* and an annular shoulder on the body *a*.

The body *a* and the bushing *e* are provided with two end air ports *g*, *g'*, with a central port *h* communicating with a vacuum pipe *i*, and with two other ports *k*, *k'*, located between the central vacuum port and the end air ports respectively and communicating respectively with nozzles *m*, *m'*, adapted for connection with tubes connected with the inflation chambers of the teat cups (not shown). Such tubes are usually of rubber or other flexible material, the ends of which are slipped over the nozzles.

The reciprocable motor valve piston *n* is provided with axial end passages *o* and *r*, with a passage *p* and port *q* in constant communication with passage *o*, and with a passage *s* and port *y* in constant communication with passage *r*. Passage *o* is in constant communication with the left-hand end *v* of the piston chamber. Passage *r* is in constant communication with the lower diaphragm chamber *t*.

The upper (right-hand) end of the valve piston *n* extends into the lower diaphragm chamber *t* and is connected with the diaphragm *d* by means of a yoke *w* secured to the diaphragm, the free end of the yoke engaging an annular groove near the end of the valve piston. The yoke *w* is secured to the diaphragm by means of a screw *x*, a screw nut *z* and a lock nut *g*. By this construction, the diaphragm and valve piston may have, if desired, limited independent movements, but the preferred fit is merely that required for bare clearance. The stroke of the piston valve to the left is limited by yoke *w* contacting bushing *e* and such contact is made before the left-hand end of the piston contacts with washer *f*, so that the full diameter of such end of the piston, when so shifted, is always open to atmospheric pressure, as hereinafter described. The stroke of the piston to the right is limited by screw *x* contacting with the end wall of chamber *u*.

The two diaphragm chambers are in constant communication by means of a passage *10*. Within the passage is a sleeve *11*. A regulating screw *12* having a needle valve end extends into the sleeve, whereby the rate of flow of air between the diaphragm chambers is controlled, thereby controlling the rate of pulsation.

Assume the piston valve to be shifted to the right, as shown in Fig. 5. Piston chamber *v* then connects with vacuum through port *h*, passage *p*, port *q* and passage *o*. Nozzle *m'* connects with vacuum pipe *i* through port *h*, passage *p* and port *k'*. Nozzle *m* connects with air port *g* through passage *s* and port *k*. Diaphragm chamber *t* connects with air port *g* through passage *s*, port *y* and passage *r*. The right hand end of the piston valve is thus subjected to atmospheric pressure.

and the left hand end to vacuum, and the valve would, if unrestrained, immediately shift to the left. However, when, in the movement to the right, the valve connects diaphragm chamber *t* with the atmosphere diaphragm chamber *u* is (as will be hereinafter described) under a pressure only slightly greater than the half atmospheric pressure in vacuum pipe *i* and due to the area of the diaphragm greatly exceeding the areas of the

10 piston ends the pressure acting to hold the valve greatly exceeds the unbalanced pressure on the valve tending to move it to the left. Due to the unbalanced pressures in the two diaphragm chambers, air flows from chamber *t* through passage *10* to chamber *u*. As soon as the amount of air is such as to raise the pressure in chamber *u* to nearly atmospheric so as to reduce the pressure difference in the two chambers to just below the pressure difference on the two valve ends, the 20 valve is shifted to the left, as shown in Fig. 6. As before mentioned, this pressure difference on the two valve piston ends is one established by the valve itself in its movement to the right.

It may be added that in the central part of the valve-shifting movement to the left, the ports *g'*, *g* and *h* are closed. But air continues to flow from the chamber *t* to the chamber *u*, although very slowly due to the pressures being nearly balanced at the beginning of this shift, thus further

30 reducing the resistance to movement toward the left so that the movement continues even though there is no increase of the positive forces tending to cause movement. To be quite exact, it should be pointed out that at the beginning of this shift 35 the inflation spaces of the two teat cups that are connected with nipple *m* are under atmospheric pressure, while the inflation spaces of the two teat cups that are connected with nipple *m'* are under vacuum. The two teat cups and their 40 tube connections to nipples *m* and *m'* act as air reservoirs which, during the movement of the piston across center, maintain substantially the same atmospheric pressure in chamber *t* and substantially the same vacuum in valve chamber *v* that exists therein at the beginning of the shift. After the slight movement beyond center required to open port *h* and connect chamber *t* with vacuum, the movement of the valve to the left is quickly completed, since at this time chamber *u* is under nearly atmospheric pressure and chamber *t* connects (through passage *r*, port *y*, passage *s* and port *h*) with vacuum, so that the pressure required to complete the movement of the valve to the left and hold it there greatly exceeds the pressure which, by the opening of port *g'*, is now (through passage *p*, port *q* and passage *o*) established in valve chamber *v*.

At the same time the above connections are established, nozzle *m'* (communicating with one pair of teat cups) connects with air port *g'* through port *k'* and passage *p* and nozzle *m* (communicating with the other pair of teat cups) connects with vacuum pipe *i* through port *h*, passage *s* and port *k*. Since the left hand end of the piston valve is thus subjected to atmospheric pressure and the right hand end to vacuum the valve would, if unrestrained, immediately shift to the right. However when, in the described movement of the valve to the left the valve connects diaphragm chamber *t* with vacuum, diaphragm chamber *u* is, as above described, under nearly atmospheric pressure, and the pressure acting to hold the valve to the left greatly exceeds the established differential pressure on the valve tending to move it to the right; but air now flows from

chamber u through passage 10 to chamber t . As soon as amount of such air flow is sufficient to reduce the pressure in chamber u to nearly half an atmosphere so as to reduce the pressure difference in the two chambers to just below the pressure difference on the two valve ends, the valve shifts to the right; this pressure difference on the two valve ends being that established by the valve itself in its movement to the left.

In the central part of the valve-shifting movement to the right the ports g' , g and h are closed, but air continues to flow slowly from chamber u to chamber t , gradually reducing the resistance to movement to the right while the air reservoirs in the teat cups, as hereinbefore explained, maintain the established vacuum in chamber t and the established atmospheric pressure in valve chamber v until the piston moves sufficiently beyond center to open port g and connect chamber t with the atmosphere, the movement of the valve to the right being then quickly completed due to the differential pressures on the large area diaphragm greatly exceeding the atmospheric pressure on the small area in the valve chamber v .

The action of the diaphragm not only prevents the immediate return of the valve after it has completed its shift in either direction, but also, after the valve has, in either stroke, passed a distance beyond center sufficient to reverse, as described, all the pneumatic connections, the sudden unbalancing of the opposing pressures on the diaphragm insures the quick completion of the stroke of the valve.

A clearer understanding of the operation may be had by reference to the following table:

Pressure in operating chambers t , u and v

[Absolute pressures are used in this table. Atmospheric pressure=14.70 pounds per square inch]

Pressure per square inch			Left thrust			Right thrust			Total residual thrust		Piston moves
v	t	u	t	u	Total	v	t	Total	Left	Right	
7.35	14.70	7.89-	2.21	16.36-	18.57-	1.11	30.51	31.62	0+	13.05+	No. Left.
7.35	14.70	14.16+	2.21	29.41+	31.62+	1.11	30.51	31.63	0+	13.05+	No. Right.
14.70	7.35	14.16+	1.11	29.41+	30.52+	2.21	15.26	17.47	13.05+	0+	
14.70	7.35	7.89-	1.11	16.36-	17.47-	2.21	15.26	17.47	-----	-----	

It is assumed in the above table that the atmospheric pressure is 14.7 pounds to the square inch and that the "vacuum" is equal to half atmospheric pressure, or 7.35 pounds to the square inch. The numbers in the first three vertical columns show pressures to the square inch in piston chamber v and diaphragm chambers t and u . The figures in the next six vertical columns indicate pounds (or other units) of absolute pressure in these chambers, giving proper value to the relative pressure areas of the diaphragm faces and the ends of the piston.

The numbers in the first horizontal column of numbers indicate pressures when the piston has completed its stroke to the right, at which time air at full atmospheric pressure is admitted to chamber t , while piston chamber v is connected with vacuum. At this time the pressure opposing movement of the piston to the left greatly exceeds that tending to cause such shift and a large volume of air must flow from chamber t to chamber u before the pressures tending to shift the piston to the left overcome the opposing pressure. The numbers in the second horizontal column indicate the pressures that must be established to shift the piston to the left. As soon as the shift of the piston to the left is completed, chamber t is connected with the atmosphere, the

numbers in the third horizontal column indicating pressures when the shift to the left is completed. At this time the pressure opposing movement of the piston to the right greatly exceeds that tending to cause such shift and a large volume of air must flow from chamber u to chamber t before the pressure tending to shift the piston to the right overcomes the opposing pressure. The numbers in the fourth horizontal column indicate the pressures that must be established to shift the piston to the right.

The operation would not be essentially different if the valve pistons were connected directly to the diaphragm, as shown in Fig. 7. In this modification the areas of the opposing faces of the diaphragm are different to the extent of the cross-sectional area of the valve piston, and the effective absolute pressure on the right hand end of the valve piston is the absolute pressure on the right hand face of the diaphragm over an area equal to the cross-sectional area of the valve piston. In such a modification the residual thrust numbers are the same as in the above table. The two constructions are therefore equivalents.

It is entirely practicable to so construct the pulsator that the diaphragm will be not under tension when it is midway between its two opposite distended or flexed positions and so that in this position of the diaphragm the pulsator will be in an exactly central position. In such a construction, if the pulsator is positioned vertically, the weight of the valve will cause it to drop so that, when the nozzle is connected with vacuum, the pneumatic connections necessary to start the operation will be made. If, however, the pulsator

is positioned horizontally, the valve may assume a dead center position, at which position the pneumatic connections necessary to operation would not be made and the pulsator would not start to operate. Even during operation conditions may arise which would interrupt the pneumatic connections and cause the pulsator to assume a dead center position. There are certain objections to positioning the pulsator vertically, one of which is that when the pulsator is mounted on a milk pail, the handle will have to be of a considerable and objectionable length to clear the pulsator. It is therefore desirable to position the pulsator horizontally, as shown in the drawings. In this position, as shown in Fig. 1, when the diaphragm is in the unflexed position that it occupies when the pulsator is not in operation, the valve is sufficiently off dead center to just make the pneumatic connections necessary to start the pulsator. In this figure the valve is shown to the left of dead center so that vacuum port h has just barely started to open to connect diaphragm chamber t with vacuum and air port g' has just barely started to connect valve chamber v with the atmosphere.

This arrangement requires that the diaphragm shall flex from its normal position further to the right than to the left and this in turn requires

that the effective pressure acting to shift the diaphragm to the right shall be greater than that to shift it to the left. This requirement is satisfied by constructing the diaphragm, as shown in the figures, so that it comprises a central flexible and elastic disc d secured circumferentially to the cylindrical wall of the casing and plates 16 and 17 (which should be round if the chambers t and u are cylindrical) of the metal or other rigid material and of different diameters applied to the opposite sides of the disc d and secured preferably only at their centers to the center of the disc; or (at any rate) that the disc shall not be secured to the larger plate outside the circumference of the smaller plate. When the pressure is acting to hold the diaphragm to the right, as shown in Fig. 5, the part of the flexible disc d outside the plate 16 is held against the plate 17 by the higher pressure in chamber t , the effective area of the disc and plate being the area of a circle the diameter of which is equal to (approximately) one half the sum of the diameter of diaphragm d and the diameter of plate 17. When the pressure is acting to hold the diaphragm to the left, as shown in Fig. 6, the part of the flexible disc d outside the plate 16 is held away from plate 17 by the higher pressure in chamber u , the effective area of the disc and plate being the area of a circle the diameter of which is equal to (approximately) one half the sum of the diameter of the diaphragm d and the diameter of plate 16.

If we assume that the valve has shifted to the right and that thereafter a certain volume of air has flowed from chamber t to chamber u adequate to reverse the net pneumatic force (see table on page 3) and start movement of the valve to the left, the pressure in chamber t is still higher than in chamber u (see said table) and continues to hold the diaphragm in the position relative to plates 16 and 17 shown in Fig. 5 until the valve has moved sufficiently beyond dead center to open air port g' to chamber v and vacuum port h to chamber t .

If we assume that the valve has shifted to the left and that a certain volume of air (which, as hereinbefore explained, is equal to that which flowed from chamber t to chamber u after the piston had shifted to the right) has flowed from chamber u to chamber t , adequate to reverse the net pneumatic force and start movement of the valve to the right, the pressure in chamber u is still higher than in chamber t and continues to hold the diaphragm in the position relative to plates 16 and 17 shown in Fig. 6 until the piston has moved sufficiently beyond dead center to open air port g to chamber t and vacuum port h to chamber v .

While, during both of these opposite movements, the difference between the pneumatic pressures in the two chambers is the same, the pneumatic pressure in chamber t resisting movement of the diaphragm from the right end position is operative on a greater area of the diaphragm during the movement of the valve to the left (until the connections to vacuum and atmosphere are reversed) than during the movement of the valve to the right; while the pneumatic pressure in chamber u resisting movement of the diaphragm from the left end position is operative on a smaller area of the diaphragm during the movement of the valve to the right (until the connections to vacuum and atmosphere are reversed) than during the movement of the valve to the left. Since, as above explained, the diaphragm flexes from its normal position further

to the right than to the left, it is clear that when the valve and diaphragm are in the right hand position shown in Fig. 5, it is under a higher tension than when it is in the left hand position shown in Fig. 6. Therefore, in the movement of the valve to the left, a relatively strong tension of the diaphragm tending to move it to the left is opposed by a relatively strong pneumatic force acting directly thereon; while in the movement of the valve to the right a relatively weak tension of the diaphragm tending to move it to the right is opposed by a relatively weak pneumatic force acting directly thereon.

It is necessary that, at the end of both strokes of the valve, the difference between the pneumatic pressures in the two diaphragm chambers should be the same, and that, thereafter, the volume of air flowing from one side to the other should be the same. Otherwise, there would be inequality of pulsations. With the construction above described, only mechanical skill is required to so proportion the diameters of the plates 16 and 17 as to compensate for the difference between the tensions of the diaphragm, in its movement away from opposite positions, by differential pneumatic forces, acting directly on the diaphragm, resisting such tensions.

A simpler way of providing means to start the pulsator if it is on dead center is to provide a pin 14 (slidable in the cap b and washer f) provided with a head adapted, when the pin is pushed in by hand, to engage the end of the piston and shift it to or toward its right-hand position. When the pressure on the pin is released, it is retracted by a spring 15 and performs no function in the operation of the pulsator. It may happen, however, that in freezing weather, due to moisture within the pulsator, the piston will be frozen to the valve chamber. Therefore the commercial pulsator is provided with this spring pin, by means of which the pulsator may be readily freed.

By providing the pulsator with such a spring pressed pin, the described special construction of the diaphragm to insure that the pulsator will never assume a dead center position is unnecessary and it is not intended to restrict the claims thereto except as specifically claimed. Even with the use of the described special diaphragm construction, the spring-pin starter may be retained as an additional means whereby the pulsation may be positively moved to an end position. Conversely, even when the spring-pin starter is provided, it is preferable to employ the special construction of diaphragm described in order to insure against the piston valve assuming a dead center during operation in case of temporary interruption of the vacuum.

While in the foregoing description I have described those characteristics of the invention which apply to the specific embodiment of the invention illustrated and described, it should not be understood that all such characteristics are essential features of the invention, the essential features being those defined in the claims.

What I claim and desire to protect by Letters Patent is:

1. An automatic pneumatic pulsator for milking machines comprising a valve chamber, a valve reciprocable therein and a diaphragm connected with the valve, said pulsator having opposing pressure surfaces a minor area of which is afforded by the valve and a major area of which is afforded by the diaphragm, means operable in each stroke of the pulsator to make connections

with sources of high and low pressures adapted to establish comparatively high differential pneumatic pressures on said opposing pressure surfaces and thus prevent immediate reversal of the valve, and a conduit through which, after said differential pressures are established, air is adapted to flow from one side of the diaphragm to the other until the pneumatic pressures on opposing pressure surfaces are balanced and then reversed, thereby effecting the reversal of the pulsator.

2. An automatic pulsator in accordance with claim 1 comprising also two ports in the valve chamber adapted for connection with two different pairs of teat cups and means operable on one stroke of the valve to connect one port with the source of high pressure and the other port with the source of low pressure and on the other stroke of the valve to reverse said connections, said connections being established substantially simultaneously with said establishment of high differential pneumatic pressures on said opposing pressure surfaces.

3. An automatic pneumatic pulsator having openings connectable with sources of high and low pressure and comprising a reciprocable valve, a diaphragm of relatively large area connected thereto, teat cup connections, means operative on the movement of the valve in either direction to reverse the pneumatic connections to the teat cups and to immediately establish pneumatic connections to the valve tending to reverse it and differential pneumatic pressures on opposed faces of the diaphragm effective to hold the valve in the position to which it is moved, and a conduit providing a restricted passage through which air is adapted to flow from one side of the diaphragm to the other until the pressures on opposite sides of the diaphragm so nearly balance that the pneumatic pressure on the valve is effective to reverse it.

4. An automatic pneumatic pulsator for milking machines having openings connectable with sources of high and low pressure and comprising a valve chamber, a motor valve reciprocable therein, a diaphragm of comparatively large area connected to the valve and forming on its opposite sides two chambers, teat cup connections, means operable in the movement of the valve in either direction to reverse the pneumatic connections to the teat cups, to establish opposing differential pneumatic pressures on the valve tending to reverse it, and to create similar differential pneumatic pressures in the two diaphragm chambers effective to hold the valve from reversal, and a restricted passage connecting the two diaphragm chambers through which air is adapted to flow until the pressures therein are so nearly balanced that the said differential pressures on the valve are effective to reverse it.

5. An automatic pneumatic pulsator for milking machines comprising a valve chamber, a motor valve reciprocable therein, a diaphragm of comparatively large area connected to the valve and forming on opposite sides thereof two chambers, means operable in one direction of movement of the valve to connect its opposite ends with high and low pressures tending to move it in the opposite direction and to connect one of the diaphragm chambers with the source of high pressure while the other chamber is under low pressure, thereby holding the valve from so moving, there being a restricted passage connecting the two chambers through which air is adapted to flow until the pressures in the two chambers are so nearly equalized as to enable the valve

to be moved by the differential pressures operative thereon, and means operable in the other direction of movement of the valve to reverse the pneumatic connections to its opposite ends and thereby tend to reverse it and to connect the first named diaphragm chamber with the source of low pressure, thereby holding the valve from reversing until by the flow of air through said passage in the opposite direction the pressures in said chambers are again so nearly equalized as to enable the valve to be reversed by the differential pressures operative thereon.

6. An automatic pneumatic pulsator for milking machines comprising a cylindrical piston chamber, a diaphragm of relatively large area, a piston valve connected to the diaphragm and reciprocable in the piston chamber, the piston chamber having two ports adapted for connection with two pairs of teat cups, means operable in the reciprocation of the piston valve in one direction to connect with a source of low pressure one of said ports and the end of the valve chamber remote from the diaphragm and to connect with a source of high pressure the other of said ports and one side of the diaphragm while the other side of the diaphragm is under low pressure, thereby holding the piston valve from moving in the opposite direction, a conduit connecting opposite sides of the diaphragm through which air flows until the pressures on opposite sides of the diaphragm are nearly balanced, thereby enabling the valve to move in the last named direction, and means operable in the movement of the valve in the last named direction to connect with a source of high pressure the first named port and the end of the valve chamber remote from the diaphragm and to connect with a source of low pressure the second named port and the first named side of the diaphragm while the other side of the diaphragm is under high pressure, thereby holding the valve from moving in the first named direction, air thereupon flowing through said conduit until the pressures on opposite sides of the diaphragm are again nearly balanced, thereby enabling the valve to move in the first named direction, the second named side of the diaphragm being closed from communication with sources of high and low pressure except through said conduit.

7. An automatic pneumatic pulsator for milking machines comprising a valve chamber having two ports adapted for connection with two pairs of teat cups and also ports communicating with atmosphere and vacuum, a motor valve reciprocable therein and adapted in its movement in one direction to connect one end of the valve and one of the teat cup ports with vacuum and the other end of the valve and the other teat cup port with the atmosphere and adapted in its movement in the other direction to reverse said connections, whereby the valve acts as a motor to effect its own reciprocation, a diaphragm of comparatively large area connected with the valve, means operative in opposite strokes of the valve to provide free communication between one side of the diaphragm and atmosphere and vacuum respectively, and an air conduit connecting opposite sides of the diaphragm, whereby at each end stroke of the valve high differential pressures are immediately established on opposite sides of the diaphragm to thereby hold the valve from reversing itself until flow of air through said conduit so nearly balances the said opposing pressures on the diaphragm that the differential pressure on the valve is effective to reverse it.

8. In an automatic pneumatic pulsator for milking machines, a cylindrical valve chamber, a piston valve reciprocable therein, ports and passages whereby when the piston is at either end of its stroke the near end will have unrestricted connection with a maximum high pressure and the other end unrestricted connection with a minimum low pressure, a diaphragm having an area multiple times that of the piston and having its side adjacent the piston always exposed to the same pressure as the adjacent end of the piston and a passage whereby restricted communication is always open from the space directly adjacent one side of the diaphragm to the space directly adjacent the other side thereof.

9. In an automatic pulsator for milking machines, a cylindrical valve chamber, a valve piston reciprocable therein, ports and passages so located that when the piston reaches either end of its stroke the advanced end will be connected with a source of high pressure and the trailing end with a source of low pressure, such differential pressures thereby tending to immediately reverse the piston, ports adapted for connection with two different pairs of teat cups, one port being always exposed to the same pressure as one end of the piston and the other port being always exposed to the same pressure as the other end of the piston, pneumatically actuated means operable at each stroke of the piston first to establish unbalanced pneumatic pressures greatly superior to the differential pneumatic pressures on opposite ends of the piston and hold said piston from reversal and then to gradually reduce said unbalanced pressures until they become inferior to the differential pneumatic pressures on opposite ends of the piston, thereby effecting a reversal of the piston.

10. An automatic pulsator for milking machines comprising pneumatically reciprocable means having opposing pneumatic major pressure areas and opposing minor pressure areas, said means including a pneumatically reciprocable valve, means, including ports and passages, operable in one stroke of the valve to connect one major pressure area and one opposing minor pressure area with a source of high pressure and the other minor area with a source of low pressure and in the other stroke of the valve to reverse said connections, and a restricted passage through which after one stroke of the valve air flows from the last named major pressure area to the other major pressure area until both are under nearly equal high pressures and through which after the other stroke of the valve air flows from the second major pressure area to the first major pressure area until both are under nearly equal low pressures, thereby in each case causing the high pressure on one minor area to reverse the valve.

11. An automatic pulsator for milking machines comprising a diaphragm chamber and a piston chamber, a piston in the piston chamber, means operable in opposite strokes of the piston to connect one side of the diaphragm with sources of high and low pressure respectively; there being a passage connecting opposite sides of the diaphragm through which after each stroke of the piston a restricted flow of air nearly equalizes the pressures on opposite sides thereof, and means operable in opposite strokes of the piston to establish thereon pressures adapted respectively to move the piston in one direction when the nearly equal pressures on opposite sides of the diaphragm are high, and in the other direction

when the nearly equal pressures on opposite sides of the diaphragm are low.

12. A pulsator comprising a casing and a diaphragm dividing the same into a main chamber and a secondary chamber, means allowing restricted air flow between said chambers, a piston chamber, a piston therein connected with said diaphragm and having a pressure face at one end opening into said main chamber and a pressure face at the other end opening into a pressure chamber of small area relative to that of the diaphragm, and means operable, in one stroke of the piston, to connect the main chamber and pressure chamber with high and low pressures respectively and in the other stroke of the piston to reverse said connections, said last named connections being so relatively unrestricted as to immediately establish said pressures, the piston thereby tending to reverse itself immediately after each stroke but being held from reversal until said restricted air flow between said chambers so nearly balances the differential pressures on the diaphragm that the differential pressures on the opposite pressure faces of the valve become effective to effect said reversal.

13. A pulsator comprising passages connectable with sources of high and low pressures, a casing and a diaphragm therein dividing the same into a main chamber and a secondary chamber, means allowing restricted flow of air between said chambers, the secondary chamber being sealed from communication with said sources of high and low pressures except through the main chamber as above specified, a piston chamber, a piston therein connected with said diaphragm and having a pressure face at one end opening into said main chamber and a pressure face at the other end opening into a pressure chamber of small area relative to that of the diaphragm, and means operable, in one stroke of the piston, to connect the main chamber and pressure chamber with high and low pressures respectively and in the other stroke of the piston to reverse said connections, the said last named connecting means allowing such free flow of air that at the completion of each stroke said pressures are quickly established.

14. A pulsator comprising a casing and a diaphragm dividing the same into a main chamber and a secondary chamber, a piston chamber, a piston therein connected with said diaphragm and having a pressure face at one end opening into said main chamber and a pressure face at the other end opening into a pressure chamber of small area relative to that of the diaphragm, and means operable, in one stroke of the piston, to connect the main chamber and pressure chamber with high and low pressures respectively and in the other stroke of the piston to reverse said connections, and means allowing restricted flow of air between said diaphragm chambers whereby after the first stroke of the piston the pressure in the secondary chamber is increased by said air flow until it so nearly balances the high pressure in the main chamber that the high pressure on the face of the piston opening into the main chamber effects the second named stroke of the piston and whereby after the second named stroke of the piston the pressure in the secondary chamber is decreased by said air flow until it so nearly balances the low pressure in the main chamber that the high pressure on the face of the piston opening into the small chamber effects the first named stroke of the piston.

15. A pulsator comprising passages connectable

with sources of high and low pressure, a diaphragm casing of relatively large area and a piston chamber of relatively small area, a diaphragm dividing the casing into a main chamber and a secondary chamber, means providing a restricted passage between the chambers, the secondary chamber being sealed from communication with said sources of high and low pressure except through said main chamber, a third chamber, a valve piston connected with said diaphragm and having one end face exposed to the pressure in the main chamber and the other end face exposed to the pressure in the third chamber, and means operable in one shift of the piston to provide unrestricted communication between the main chamber and the source of high pressure and between the third chamber and the source of low pressure and in the other shift of the piston to reverse said connections, whereby at opposite strokes of the piston the pressure in the main chamber is immediately respectively raised to maximum and reduced to minimum, while between shifts the flow of air through said restricted passage continues until the opposing pressures on the diaphragm so nearly balance as to permit the shift of the piston, one shift being thereby effected when the pressures on both sides of the diaphragm are high and the other shift being effected when the pressures on both sides of the diaphragm are low.

16. A pulsator comprising passages connectable with sources of high and low pressure, a diaphragm casing of relatively large area and a piston chamber of relatively small area, a diaphragm dividing the casing into a main chamber and a secondary chamber, means providing a restricted passage between the chambers, the secondary chamber being sealed from communication with said sources of high and low pressure except through said main chamber, a third chamber remote from the diaphragm, a valve piston connected with said diaphragm at one end, the other end being constantly exposed to the pressure in the third chamber, and means operable in one shift of the piston to afford unrestricted communication between the source of high pressure and the main diaphragm chamber and between the source of low pressure and the third chamber and in the other shift of the piston to reverse said connections, whereby after the shift of the piston in one direction the pressure in the main chamber is continuously at its maximum while the pressure in the secondary chamber rises until it nearly reaches the maximum pressure in the main chamber, whereupon the piston shifts in the opposite direction and whereby after the shift of the piston in the opposite direction the pressure in the main chamber is continuously at its minimum while the pressure in the secondary chamber falls until it nearly reaches the minimum pressure in the main chamber, whereupon the piston shifts in the first named direction.

17. A pulsator comprising a casing and a diaphragm dividing the same into a main chamber and a secondary chamber, a motor valve piston in the piston chamber one end of which extends into the main chamber and is connected with the diaphragm and has at that end a pressure face exposed to the pneumatic pressure in the main chamber, a third chamber at the other end of the piston, which other end has a pressure face subject to the pneumatic pressure in said third chamber, the diaphragm being of much larger area than the piston faces, means oper-

able in one stroke of the piston to provide unrestricted communication between a source of high pressure and said main chamber while the secondary chamber is under low pressure and unrestricted communication between a source of low pressure and said third chamber, the piston thereby tending to immediately reverse itself but being held from reversal by the high pressure in the main chamber, means providing a restricted air passage between said main and secondary chambers through which air flows from the main chamber to the secondary chamber until the pressure in the secondary chamber nearly equals the high pressure in the main chamber, whereupon the superior pressure on the pressure face of the piston adjacent the diaphragm becomes effective to reverse it, and means operable in said reversal stroke of the piston to provide unrestricted communication between the source of low pressure and said main chamber and unrestricted communication between the source of high pressure and said third chamber, the piston thereby tending to immediately reverse itself but being held from reversal by the high pressure in the secondary chamber, air thereupon flowing through said restricted passage from the secondary chamber to the main chamber until the pressure in the secondary chamber is reduced to nearly that of the low pressure in the main chamber, whereupon the superior pressure on the pressure face of the piston remote from the diaphragm becomes effective to reverse the piston.

18. An automatic pulsator for milking machines comprising pneumatically reciprocable means having opposing pneumatic pressure surfaces, said means including a pneumatically reciprocable valve, means, including ports and passages connectible with sources of high and low pressure and adapted during the movement of the valve in one direction to connect certain of said opposing pressure surfaces with sources of high and low pressure respectively and thereby establish high differential pneumatic pressure on opposing pressure surfaces adapted to hold the valve at the end of its stroke and during the movement of the valve in the opposite direction to reverse said pneumatic connections and hold the valve at the end of its stroke, a continuously open air flow passage directly between two only of said opposing pressure surfaces one of which surfaces is continuously closed from communication with said sources of high and low pressure except through said air flow passage while the other is connectible with said sources of high and low pressure respectively at opposite end positions of the valve, the flow of air through the last named passage when the valve is at either end of its stroke effecting first a gradual reduction and then a momentary balancing of said opposing pneumatic pressures and then a reversal thereof to thereby establish low differential pneumatic pressure on opposing surfaces effective to move the valve in the opposite direction until the connections to the first named ports and passages are reversed.

19. In an automatic pulsator for milking machines comprising a valve chamber, a valve reciprocable therein and ports and passages connectible respectively with sources of high and low pressures whereby, when said connections are established, the near end of the valve, at either end of its stroke, will connect with a source of high pneumatic pressure while the other end will connect with a source of low pneu-

matic pressure, thereby effecting reciprocation of the valve: the herein described improvement by which the valve is made self starting, which comprises a diaphragm so secured to the valve that, when not under tension and before said differential pneumatic connections are established, it will hold the valve off center and in such connection with said ports and passages that when said differential connections are established the valve will start operation, there being an air-flow passage between opposite sides of the diaphragm tending to equalize the pressures thereon, one side of the diaphragm communicating with the ports and passages communicating with one end of the valve, said diaphragm thereby being subjected, at either end position of the valve, to a pneumatic force resisting, but not preventing, movement of the valve when the pressures on opposite sides of the diaphragm nearly reach equilibrium; said diaphragm comprising a flexible member and rigid reinforcing members of different areas applied to opposite sides of the diaphragm, thereby enabling equal pneumatic pressures to be operative on different areas of the diaphragm during movements of the valve from opposite end positions, said equal pneumatic pressures thus opposing a greater resistance to movement of the valve in one direction than in the other direction to compensate for the greater tension of the diaphragm in one of such movements than in the other of said movements.

20. An automatic milking machine pulsator comprising a valve chamber, a motor valve reciprocal therein, a diaphragm connected and movable with said valve, means, including ports and passages, adapted, during one stroke of the valve to connect one end of the valve and one side of the diaphragm with a relatively high pneumatic pressure and the other end of the valve with a relatively low pneumatic pressure and in the opposite stroke of the valve to reverse said connections, there being a passage between opposite sides of the diaphragm through which, after each stroke of the valve, air flows, the pneumatic pressure on one side of the diaphragm resisting the pressure tending to move the valve in one direction and the pneumatic pressure on the other side of the diaphragm resisting the pressure tending to move the valve in the other direction, said resisting pressures being effective to prevent movement of the valve until by flow of air through the last named passage the pressures approach equality, said diaphragm being so located relative to the valve that when the diaphragm is in its intermediate position and not under tension the valve is off center and in position to make one of the above specified pneumatic connections to the valve and diaphragm, said diaphragm comprising a flexible member and rigid reinforcing members of different areas applied to opposite sides of the flexible member, whereby the pneumatic pressure operative upon the diaphragm to resist movement of the valve is higher when the valve, at one end of its stroke, imposes a relatively high tension on the diaphragm than when the valve, at the other end of its stroke, imposes a relatively low tension thereon.

21. An automatic pulsator for milking machines comprising pneumatically reciprocal means movable in unison and having opposing pressure faces, said means comprising only a single pneumatically reciprocal valve, ports, continuously connected with sources of relatively high and low pneumatic pressure respectively,

passages adapted in and by the movement of the valve in each direction to so connect all except one of said pressure faces with said sources of relatively high and low pressures while connecting none of them simultaneously with more than one of such sources as to establish differential pressures on all said pressure faces effective to hold the valve in the end position to which it is moved, there being a passage continuously directly connecting said excepted pressure face with a space adjacent an opposed pressure face and not, otherwise than through said space, connecting it with either of said pressure sources, through which last named passage, after movements of the valve in opposite directions, air flows in respectively opposite directions between said continuously connected pressure faces until in one end position of the valve the pressure on said excepted pressure face is sufficiently high, while until in the other end position of the valve the pressures on the said excepted pressure face is sufficiently low, to establish differential pressures on all said pressure faces effective to reverse the valve.

22. An automatic pulsator for milking machines comprising a single pneumatically reciprocal valve, having a face of minor pressure area, which tends to move in one direction or the other dependent upon whether said face of minor pressure area is subjected to high pressure or low pressure, said pulsator also including pneumatically reciprocal means connected to the valve for simultaneous movement and having opposing faces of major pressure areas, means, including ports and passages, operable in one stroke of the valve to connect one major pressure area with a source of high pressure and said minor pressure area with a source of low pressure, and in the other stroke of the valve to connect the last named major pressure area with a source of low pressure and said minor pressure area with a source of high pressure, each of said connections establishing such differential pressures on said opposing major pressure faces as to hold the valve from movement, a restricted passage through which after one stroke of the valve air flows from one major pressure area to the other until both are under nearly equal high pressures and through which after the other stroke of the valve air flows in the opposite direction until both major areas are under nearly equal low pressures, whereby, after each flow of air as aforesaid the tendency of the valve to shift from one position to the other becomes effective.

23. An automatic pneumatic pulsator for milking machines comprising a single system of elements reciprocal in unison and including a valve with opposed minor pressure areas and a member with opposed major pressure areas, means operable in either stroke of the valve to so connect the minor areas with sources of relatively high and low pressure as to cause a force tending to reverse the movement of the valve and to simultaneously so connect one of the major pressure areas as to oppose movement of the valve, there being a restricted passage adapted to allow flow from the high to the low pressure side of said member until the opposing pressures thereon are so nearly equalized as to permit reversal of the valve by the forces on the minor areas.

24. The herein described method of operating a milking machine pulsator having only one reciprocating valve member which comprises subjecting said valve member in one end position to opposing relatively high and low pneumatic pres-

sures to thereby hold it in that position, gradually increasing the low pressure by providing restricted flow from a zone of high pressure to a zone of low pressure until opposing pressures are barely reversed, thereby moving said valve member toward the other end position and thereafter quickly reducing the first established high pressure to low pressure to thereby enable the opposing last established high pressure to hold said valve member in the last named end position, and gradually decreasing the last established high pressure by providing restricted flow between the same pressure zones above specified until opposing pressures are barely reversed, thereby returning said valve member toward the first named end position and 15

thereafter quickly increasing the last established low pressure to high pressure to thereby establish the differential pressures first above specified, establishing the flow of air, required to effect said gradual and sudden reversals of pressure, partly by flow of air between the zones of opposing pressures above specified and partly by flow of air to one of said pressure zones from a source of high pressure and partly by flow of air from the last named pressure zone to a source of low pressure, and controlling said flow of air solely by said valve member in its shift from one end position to the other.

CYRUS HOWARD HAPGOOD.
